FILTER CARTRIDGE FOR AQUARIUMS

Herbert R. Axelrod, Deal, N.J., assignor to Miracle Pet Products, Inc., Jersey City, N.J., a corporation of New Jersey

Filed Mar. 28, 1969, Ser. No. 16,510

Term of patent 14 years

Int. Cl. D23—01

U.S. Cl. D23—4

FIG. 1.

FIG. 2.

FIG. 3.

FIG. 4.

FIG. 1 is a perspective view showing a filter cartridge for aquariums embodying my new design;

FIG. 2 is a side elevational view in enlarged scale of said filter cartridge;

FIG. 3 is a top plan view of said filter cartridge; and
FIG. 4 is a bottom view of said filter cartridge.

I claim:

The ornamental design for a filter cartridge for aquariums, substantially as shown and described.
